AIR CIRCULATING HEATER AND FURNACE

Syllis D. Tate, Centralia, Ill.

Application May 17, 1949, Serial No. 93,788

2 Claims. (Cl. 126—106)

1

The present invention relates to improvements in an air circulating heater and furnace and has for an object the provision of a device of this kind in which the air is more effectively heated and better circulated than heretofore.

Another object of the present invention is to provide an improved heater and furnace in which the air heating chamber or oven is entirely enclosed by the casing which contains the heating unit and the heated air compartment completely encloses the stove or heater containing casing.

A further object of the present invention is to provide an improved structure of this character in which the cool air intake for the oven extends through the heating unit so that the cool air is preheated before it is delivered to the oven.

A still further object of the present invention is to provide an improved heater and furnace in which means are incorporated for retaining the incoming cool air in the lower part of the oven so that it will be subjected directly to the heat from the heating unit for a longer period.

The present invention aims to provide an improved structure of this character in which the oven is fume-tight and air-tight from the heater casing so that the air heating chamber is sealed off from any fumes from the burner.

The present invention also aims to provide an improved heater and furnace in which the gas fumes and the heat from the burner are caused to travel up through the space between the oven walls and the walls of the heater casing through baffles so that these walls will retain the heat for a longer period of time.

The present invention contemplates providing an improved structure of this type in which means are provided for effecting a forced circulation of the heated air into the rooms to be heated and that a blower is utilized for feeding fresh cool air to the oven chamber.

With the foregoing and other objects in view, the invention will be hereinafter more fully described and more particularly pointed out in the appended claims.

In the drawings, in which the same parts are denoted by the same reference numerals throughout the several views,

Figure 1 is a perspective view of the improved device constructed in accordance with the present invention and with parts broken away and in section,

Figure 2 is a side elevational view of the same with parts broken away and in section,

Figure 3 is a bottom plan view of the fresh air spreader,

2

Figure 4 is a sectional view taken on the line 4—4 of Figure 1 and looking in the direction of the arrows,

Figure 5 is a sectional view taken on the line 5—5 of Figure 2 and looking in the direction of the arrows,

Figure 6 is a top plan view of the burner unit with parts broken away,

Figure 7 is a front elevational view of the burner, and

Figure 8 is a perspective view of the improved device with parts broken away showing piping for conducting heated air to remote rooms or the like.

15 Referring more particularly to the drawings, an outer shell, generally indicated at A, comprises a top 10, a bottom 11, a front wall 12, a rear wall 13 and side walls 14 and 15. This outer shell is adapted to be supported by legs 16 on a floor or the like of a building so that the bottom 11 is disposed in vertically spaced relation to the floor. The lower edge portions of the front, back and side walls of the outer shell between the legs 16 are cut away as at 17 and 20 the front and rear and side edge portions of the bottom 11 are cut away as at 18 in alignment with the corresponding cut away portions 17 to permit air to pass therethrough. The upper portions of the sides 14 and 15 of the shell are provided with perforations 19 and 20 and the top 10 of the shell is provided with similar perforations 21.

A stove or heater containing casing, generally indicated at B, is mounted within the outer shell 35 A and comprises a top 22, a bottom 23, a front wall 24, a rear wall 25 and side walls 26 and 27. The heater casing is supported within the outer shell by any suitable number of brackets 28 and 29 which may be in the form of angle irons or the like. The vertical leg of each bracket 28 is secured to the inner face of the side wall 14 of the outer shell and its horizontal leg is secured to the bottom 23 of the heater casing by rivets or the like. Similar brackets 28 may be secured to the opposite side wall 15 of the outer shell and to the bottom 23 of the heater casing. The brackets 29 may have their vertical legs secured to the inner faces of the side walls 14 and 15, respectively, of the outer shell and the outer face of the top 22 of the heater casing by the rivets or the like.

The bottom 23 of the heater casing is provided with perforations 30 so that the air which passes through the cut away portions 17 and 18 of the outer shell can enter the heater casing to supply the air necessary to support combustion for a

stove or heating unit 31. The heating unit 31 is a somewhat box-like structure and comprises an upper wall 32, a bottom wall 33, side walls 34 and front and back walls 35 and 36, respectively. The heating unit 31 is divided into transversely extending compartments 37 by partitions 38 which extend between and are secured to the side walls 34 and the upper and lower walls 32 and 33. The upper wall 32 is provided with apertures 39.

A pipe 40 is adapted to have one end connected to a suitable source of natural or manufactured gas and its opposite end terminates in two branches, each of which comprises two sections 41 and 42. The sections 41 of each branch are disposed at an angle of the order of forty-five degrees to the pipe 40 and to the sections 42 which are disposed substantially parallel to the pipe 40. The sections 41 and 42 are provided with burners 43, two of which are received by each compartment 37 by being received through appropriate openings in the lower bottom wall 33. An auxiliary pipe 44 has one end connected to the pipe 40 and its opposite end communicates with a pilot burner 45. Suitable valves 46 and 47 are provided for controlling the supply of gas through the pipes 40 and 44, respectively.

An oven, generally indicated at C, is disposed within the stove or heater containing casing B comprising a top 48, a bottom 49, side walls 50 and 51, a front and back walls 52 and 53, respectively. A fresh air inlet conduit 54 has one end connected to a blower 55 and its opposite end portion 56 is bent upwardly and passes through appropriate openings in the upper and lower walls 32 and 33 of the heating unit 31. The blower 55 is mounted upon a suitable support 55a and is provided with an air filter. The openings in the upper and lower walls of the heating unit 31 may be located at any desirable point, but in the present illustration are shown to be substantially centrally disposed. The upper outlet end of the fresh air conduit 54 is received by a suitable opening in the bottom 49 of the oven C so that the fresh air will be delivered to the interior of the oven. This opening in the bottom 49 of the oven may be disposed substantially centrally thereof.

A fresh air spreader, generally indicated at 57, is supported by the bottom 49 of the oven in vertically spaced relation to the outlet end of the conduit 54. The spreader 57 comprises a plate 58 from the under surface of which projects a cone shaped member 59 having facets 60. The apex of the cone is disposed slightly above and substantially centrally of the outlet of the conduit 54. Vanes 61 radiate outwardly from the cone shaped member 59 and have their upper edges attached to the under surface of the plate 58 and their bottom edges attached, as by welding or the like, to the upper surface of the bottom 49 of the oven C. Each vane 61 has two longitudinally curved portions 62 and 63 which are the reverse of each other. Brackets 64 which are similar to brackets 28 and 29 are secured to the inner faces of the side walls 26 and 27 of the stove or heater containing casing B and to the top and bottom 48 and 49, respectively, of the oven C for supporting the oven within the heater casing B.

Pipes 65 extend through suitable aligned openings in the side walls 26 and 50 and 27 and 51 of the heater casing B and oven C, respectively, so that the heated air from the oven C may be conveyed to the spaces between the side walls 14

and 26 and 15 and 27 of the outer shell A and the heater casing B, respectively. The pipes 65 have a tight fit with the openings in the side walls of the heater casing B and the oven C so that no fumes of air may pass therearound. A circulating fan 66 is mounted on the rear wall 13 of the outer shell A and communicates with the space between the outer shell A and the heater casing B by an inlet pipe 67.

10 A baffle 68, which may be in the form of an elongated strip, has its forward end portion attached as at 69 by welding or the like to the inner face of the front wall 24 of the heater casing B. The baffle 68 extends rearwardly and upwardly at an angle of the order of forty-five degrees to the front wall 24 in the space between the side wall 27 and 51 of the heater casing B and the oven C, respectively. The rear end of the baffle 68 terminates short of the rear wall 25 of the heater casing B and the side edges of the baffle are attached to the inner and outer faces of the side walls 27 and 51, respectively, as by welding or the like.

A baffle 70 which may be similar in shape and construction to the baffle 68 has its rear edge attached by welding or the like, as indicated at 71, to the inner face of the rear wall 25 of the heater casing B. The baffle 70 extends forwardly and downwardly at an angle of the order of forty-five degrees to the rear wall 25 and substantially parallel to the baffle 68. The major portion of the baffle 70 is disposed in spaced apart vertical alignment with the major portion of the baffle 68 and the lower forward end of the baffle 70 terminates short of the front wall 24 of the heater casing B. The side edges of the baffle 70 are attached to the inner and outer faces of the side walls 27 and 51 of the heater casing B and the oven C, respectively.

Baffles 71 and 72 which are similar in structure and arrangement to the baffles 68 and 70, respectively, are disposed in the space between the side walls 26 and 50 of the heater casing B and the oven C, respectively.

An escape vent 73 for the fumes from the heating unit 31 extends through suitable openings in the rear walls 13 and 25 of the outer shell A and the heater casing B. The inner end of the vent 73 communicates with the interior of the casing B and its outer end exhausts to the outside atmosphere.

When the heater or furnace is to be employed for heating room remote from the furnace, in lieu of the perforations 19, 20 and 21, the pipes 65 are extended through and outwardly of the side walls 14 and 15 of the outer shell A. The outer extended ends of the pipes 65 are connected to conduits 74 which lead to the room to be heated. A door 75 is disposed in the front wall 12 of the outer shell A.

The heater or furnace may be made of any size suitable for the area to be heated. For example, the unit for a five room house would measure 46 inches in height, 24 inches in width and 20 inches in depth. These are the dimensions for the outside shell A. In this size unit the casing B would be 40 inches in height, 18 inches in width and 16 inches in depth and the measurements for the oven C would be 16 inches in height, 14 inches in width and 12 inches in depth.

The side walls 14 and 15 of the outer shell A are provided with louvres 77.

In the use of the device the blower 55 forces fresh air through the conduit 54 and through its end portion 56 into the lower portion of the

oven C against the under surface of the fresh air spreader 57. The fresh air as it passes through the heating unit 31 by means of the portion 56 of the conduit 54 will be preheated to some extent. The incoming fresh air will strike the facets 60 of the cone shaped shaped member 59 and will thereby be directed against the vanes 61. The fresh air follows the reverse curvatures 62 and 63 of the vanes 61. This arrangement causes the air to take a tortuous path so that it is retained for a relatively long period in contact with the bottom 49 of the oven C where it is subjected to the direct heat of the heating unit 31. The heated air then rises upwardly along the side walls 50 and 51 of the oven C and flows outwardly therefrom through the pipes 65. The pipes 65 deliver the heated air into the spaces between the side walls 14 and 26 and 15 and 27 of the outer shell A and heater casing B, respectively. From these spaces the air is forced outwardly through the perforations 19, 20 and 21 by the circulating fan 66.

The fumes from the heating unit 31 will flow upwardly as indicated by the arrows 76 against the under surface of the baffle 68 and above and below the baffles 68 and 70, respectively. The fumes will then move upwardly around the forward end of the baffle 70 and will rise to the upper portion of the heater casing B and be discharged from the vent 73. The baffles 71 and 72 will exert a similar influence upon the fumes coming in contact therewith. With this arrangement a back and forth movement is imparted to the fumes from the heating unit 31 so that the heated fumes are maintained in contact with the side walls of the oven and heater casing for a relatively long period of time. This will materially increase the heating effect of the heating unit 31 upon the air in the oven and the air in the space between the outer shell A and the heater casing B. Air for supporting the combustion of the heating unit 31 flows through the cut away portions 17 and 18 of the outer shell A and through the perforations 39 in the bottom 23 of the heater casing B and thence to the heating unit 31.

It is obvious that various changes and modifications may be made in the details of construction and design of the above specifically described embodiment of this invention without departing from the spirit thereof, such changes and modifications being restricted only by the scope of the following claims.

What I claim is:

1. A gas circulating heater and furnace comprising an outer shell having air inlet openings at its lower end, a heater casing mounted within the shell in spaced relation thereto and having air inlet openings in its lower end, an air heating oven mounted within the casing adjacent the

upper end thereof and in spaced relation thereto, said oven having a bottom wall formed with an opening, a burner unit disposed within the casing and underlying the bottom of the oven and comprising an enclosed casing including spaced apart upper and lower walls the upper of said walls having burner orifices therethrough, means for supplying fuel to the space between said upper and lower walls, said burner unit walls having vertically aligned openings therethrough, a fresh air inlet duct extending through said shell and casing and having a substantial portion disposed within said heater casing and adjacent to said burner unit, said duct also having a portion extending upwardly through the openings in the walls of the burner unit and communicating with the opening in the bottom wall of the oven, an air spreader mounted on the bottom of the oven and transversely overlying the opening to cause the air to flow transversely over the bottom of the oven, conduit means conveying heated air currents from the oven to the space between the casing and shell, and means for conducting the heated air currents from the space between the casing and shell and delivering them outwardly of said shell.

2. The combination of claim 1 wherein said oven is substantially air tight except for its fresh air inlet opening and its heated air conduit means and said conduit means includes tubes disposed transversely between the side walls of the oven and casing and in the space between the oven and casing and said conducting means includes a circulating fan communicating with the space between the casing and shell and said shell having openings in the side walls thereof.
